Robert I. Anderson, Grand Haven, and Bert Hoeker, Muskegon, Mich., assignors to The Brunswick-Balke-Collender Company, Chicago, Ill., a corporation of Delaware

Application March 13, 1946, Serial No. 127,451

Term of patent 14 years

(Cl. D34—5)

To all whom it may concern:

Be it known that we, Robert I. Anderson and Bert Hoeker, both citizens of the United States, residents, respectively, of Grand Haven, in the county of Ottawa, State of Michigan, and of Muskegon, in the county of Muskegon, State of Michigan, have jointly invented a new, original, and ornamental Design for a Combined Score Table and Score Projector or Similar Article, of which the following is a specification, reference being had to the accompanying drawings, forming a part hereof.

Fig. 1 is a perspective view, looking at the front of a combined score table and score projector or similar article, showing our new design;

Fig. 2 is a perspective view thereof, looking from the rear.

We claim:

The ornamental design for a combined score table and score projector or similar article, as shown.

ROBERT I. ANDERSON.
BERT HOEKER.
